MINE CAR END CONSTRUCTION

William F. Dietrichson, Berwick, Pa., assignor to
American Car and Foundry Company, New
York, N. Y., a corporation of New Jersey

Application August 17, 1935, Serial No. 36,644

25 Claims. (Cl. 105—364)

This invention relates to improvements in mine and similar rail or industrial cars.

Mine cars are generally of either the rotary dump, end dump or drop bottom type and each type has previously been built with an end or sill construction peculiar to that type. The wide variance in types of ends necessarily resulted in higher costs and delays in construction, since each type of car needed a different type of end and it is an object of this invention to provide a simple cast end member that is suitable for use in either type of car.

Another object of the invention is the provision of a cast metal end member adapted to receive resilient bumping means.

A further object of the invention is the provision of a one-piece metal end member that is adapted for use in end dump mine cars.

A still further object of the invention is the provision of a one-piece metal end member of great strength having a large side sill contacting area.

These and other objects of the invention will be apparent to one skilled in the art after a study of the following description in conjunction with the accompanying drawings, in which

Figure 1 is a central sectional view through a mine car having the improved end members attached and with the central portion of the car eliminated in order to more clearly show the end members;

Fig. 2 is a plan view of the mine car showing the end members and with the central portion of the car broken away;

Fig. 3 is a front view of one-half of the member shown at the right side of Fig. 1;

Fig. 4 is a front view of one-half of the member shown at the left side of Fig. 1;

Fig. 5 is a sectional view taken through the spring of Fig. 6 and showing a modification of the device of Fig. 1; and

Fig. 6 is a plan view of a little more than half of the modified end construction of Fig. 5.

Referring now to the drawings in detail, it will be seen that the car, fragments of which are shown in Fig. 1, is built with end members A and B, each being formed in one piece and having extended contact with the side sills. The member A has provision for a wooden buffer block and the member B is so formed as to take a combined spring draft and buffering gear such as shown in Patent 2,012,114 granted August 20, 1935. It is obvious, of course, that under certain conditions both buffer members may be of the spring type or of the wood bumper type, but it has been found that an arrangement such as shown is very satisfactory and stands up well in service.

The end member A is formed in one piece, preferably by casting, having a substantially ver-

tical web 2, substantially horizontal rearwardly directed flange 4, horizontal outwardly extending upper and lower spaced apart flanges 6 and 8 respectively, and rearwardly inclined flange 10, all of which extend substantially continuous from side to side of the member. Gussets 12 of any desired number brace the flange 8 and web 2, and extensions 14 of these gussets connect and mutually brace the web 2, flange 4 and inclined flange 10, thus forming an extremely rigid end member of large section modulus. The flange 4 has widened portions 16 adjacent each gusset 14 and side wall, which portions are provided with holes 18 to receive rivets in order that the usual belt or binder (not shown) may be attached if desired.

The top flange 6 and bottom flange 8 are provided with elongated slots 20 adapted to receive securing means, such as bolts, which will secure in position the wood block 22 and metal bumper cap (not shown). The slots provide for longitudinal movement of the metal bumper relative to the flanges in order that the securing means will not be sheared. The wood block abuts against the web which is well braced by the gussets and various flanges. Coupler tongue 24, of T or other suitable cross section, is formed integral with the member and extends upwardly and outwardly from the web to receive a coupling pin (not shown) adapted to be inserted in openings 26 of the tongue and openings 28, 30 and 32 extending through the respective flanges and wood block.

The flange 10 is inclined at the desired angle to give greatest bracing effect and to form a suitable chute for discharge of material if the car is of the end dump type. The flange is provided with openings 34 to receive rivets 36 securing the floor 38 in position. It is obvious that this flange may be extended and secured to the floor in the manner shown and to be described in connection with the member B at the other end of the car.

The ends of the web and flanges are joined together by a side wall 40 which, in the instance shown, caps the end of the member and provides an extended area through which rivets 42 or other suitable securing means may be inserted. The side sills 44 are extended and have their ends coped to conform to the curvature of the flanges 6 and 8, while a flange 46 is extended outwardly from the side walls and is arranged to rest upon and be secured to the outwardly extending flange of the side sill. The rear portion of this flange is inclined as at 48 to present a smooth upper surface.

The member B is, like member A, formed in one piece with vertical web 50, horizontal lower flange 52, portions of which are situated on both sides of the web, upper flange 54 and rearwardly directed flange 56. The lower flange 52 extends

rearwardly beyond the web and has portions thereof enlarged as at 58 to take belt securing means as described in connection with member A. The flange has a fillet 60 which strengthens 5 the connection of the flange and web at the points where the rearward flange extension is slight.

The rearwardly directed bracing flange 56 extends from substantially the horizontal center of the web 50 and has a horizontal portion 62 and inclined portion 64 terminating in a horizontal portion 66 to which the floor may be secured by suitable means 68. It is, of course, obvious that the horizontal portion may be eliminated and the entire flange inclined, although with the form as shown a greater section modulus is secured. Bracing gussets 70 of any desired number join the flange 56 to the web 50 and these gussets as shown extend both above and below the horizontal portion 62, thus effectively bracing the web against any horizontal shocks.

The various flanges and web described are substantially continuous from side sill to side sill and merge with the side wall 12 which provides an extended area for reception of securing means 14 by which the member is tied to the side sills. The wall 12 is extended if desired to provide a sill securing portion 76, part of which 78 is offset to accommodate the upturned edge of the floor sheet. A horizontal flange 80 extends outwardly from the side wall and is arranged to be secured to the side sill flange and also merge with an extension 82 of the web, which extension is provided for the reception of the end sheet (not shown).

The top and bottom flanges are provided with reenforced elongated slots 84 for reception of the draft pin and with reenforced holes 86 for the reception of bumper securing bolts (not shown). The top and bottom flanges, vertical web 50 and side walls 72 form a pocket in which a combined spring draft gear and bumper is adapted to be inserted. It is believed unnecessary to disclose this unit in position as it is fully shown and described in Patent 2,012,114 and by reference to this patent it is obvious that the unit may be simply set in the pocket provided and the securing bolts and coupling pin inserted through the holes provided in order to form the complete assembly.

The member C shown in Figs. 5 and 6 is somewhat similar to member A, but has been adapted for use of a spring bumper. In this form the web 90 has upper and lower outwardly directed horizontal flanges 92, 94 respectively, and rearwardly directed upper and lower flanges 96, 98. The upper flange 96 has downwardly and rearwardly inclined bracing or chute portion 100 terminating in a horizontal or other suitable portion 102 to which the floor may be secured by suitable means. The flange 98, as in the other forms, has portions thereof enlarged to provide portions 104 to which the belt or binder 106 may be secured.

Bracing gussets 108 connect incline 100, and flanges 96 and 98 to the web in mutual bracing relationship directly behind spring centering projections 110 formed on the outer face of the web. Spring pockets are formed by vertical ribs 112 and 114 joining the flanges 92 and 94 on either side of the centering projections and these ribs are extended slightly beyond the flanges in order to provide stops which limit the inward movement of the bumper later to be described. Each spring pocket is provided with an inspection opening 116 through which dirt may also escape from

the pocket. Elongated slots 118 are formed in the top and bottom flanges immediately adjacent the spring pockets, which slots are suitably reinforced by ribs or beads. These slots provide for movement of bumper securing bolts 120 which hold the U-shaped bumper E in position. 5

The bumper is of somewhat usual form, having a curved face with portions thereof inset to provide stiffness as well as to form the spring seats. The bumper plate is provided with slots 122 through which the coupler pin may extend, thus permitting inward movement of the bumper against the resistance of springs S.

The ends of the various flanges, web and inclined portion previously described are joined by the side wall 124, which is of a length equal to the width of the end member, and thus provides a large securing area by which the end member is fastened to the side sills 126 by means 128. A projection 130 of the wall above the incline may be used if this added securing area is necessary. The side sills, which as shown are of Z-form, have the inwardly directed flanges 132 secured to the flanges 94 and 98 to give additional stiffness and support, and these sills are extended to the outer edge of the end member in order that the entire end member may lie between the sills, thus giving a large sill securing area. A suitable coupler tongue 134 of T or other cross section is provided and is formed with a hole 136 to receive the usual coupler pin which extends also through suitable holes in the flanges 92 and 94.

startastic holes in the flanges 32 and 34. It is obvious from the description of these various one-piece end members that an extremely simple and rugged end member has been provided which is suitable for end dump cars in which case the bracing incline acts as a chute to carry the lading out of the car, and this same member when used in rotary dump cars provides a smooth corner which will prevent retention of lading in the corners. These end constructions also lend themselves readily to drop bottom cars, since the door hinge rod may be inserted through the structure below the incline which then acts as a guard for the door hinge.

which then acts as a guard for the door hinge. 45
Although the device has been shown and de-
scribed in more or less detail, it is obvious that
various modifications thereof may in the future
be necessary or desirable and that these modi-
fications may be made without departing from 50
the scope of the invention as defined by the ap-
pended claims.

What is claimed is:

- What is claimed is:

  1. A one-piece end member for rail cars comprising, a substantially vertical web extending between and connected with the side sills of the car, spaced apart flanges extending horizontally outward from one side of said web and adapted to support a bumper element, spaced apart rearwardly directed flanges extending from the opposite side of said web, one of said last named flanges having at least a portion thereof inclined downwardly toward the other flange, and spaced apart bracing members connecting said web and rearwardly directed flanges. 55
  2. A one-piece end member for rail cars comprising, a substantially vertical web, spaced apart flanges extending horizontally outward from one side of said web and adapted to support a bumper element, spaced apart rearwardly directed flanges extending from the opposite side of said web, one of said last named flanges having at least a portion thereof inclined downwardly toward the other flange, and spaced apart bracing members connecting said web and rearwardly directed flanges. 60 65

rected flanges and extending above said inclined portion for attachment to the car structure.

3. A one-piece end member for rail cars provided with spaced apart side sills and comprising, 5 a substantially vertical web extending from side sill to side sill, spaced apart outwardly directed flanges extending from one side of said web and adapted to support a bumper element, spaced apart upper and lower rearwardly directed 10 flanges extending from the opposite side of said web, and side walls connecting the ends of said flanges and web and being adapted for attachment to the spaced apart side sills.

4. A one-piece end member for rail cars provided with spaced apart side sills and comprising, 15 a substantially vertical web extending from side sill to side sill, spaced apart outwardly directed flanges extending from one side of said web and adapted to support a bumper element, spaced apart upper and lower rearwardly directed 20 flanges extending from the opposite side of said web, and side walls connecting the ends of said flanges and web, said side walls and at least one of said flanges being adapted for attachment to 25 the spaced apart side sills.

5. A one-piece end member for rail cars comprising, a substantially vertical web, spaced apart outwardly directed flanges extending from one side of said web and adapted to support a bumper element, spaced apart rearwardly directed flanges 30 extending from the opposite side of said web, side walls connecting the ends of said flanges and web and being adapted for attachment to the car structure, and means extending laterally from 35 said side walls and adapted to provide additional car attachment.

6. A one-piece end member for rail cars provided with spaced apart side sills and comprising, a substantially vertical web extending from side 40 sill to side sill, spaced apart outwardly directed flanges extending from one side of said web and adapted to support a bumper element, spaced apart upper and lower rearwardly directed flanges extending from the opposite side of said 45 web, side walls connecting the ends of said flanges and web and being adapted for attachment to the spaced apart side sills, and bracing means intermediate said side walls for connecting said web and rearwardly directed flanges.

50 7. A one-piece end member for rail cars provided with spaced apart side sills and comprising, a substantially vertical web extending from side sill to side sill, spaced apart outwardly directed flanges extending from one side of said 55 web and adapted to support a bumper element, and rearwardly convergent flanges extending substantially from side to side of said web and projecting from the opposite side of said web, side walls connecting the ends of said convergent 60 flanges and web and being adapted for attachment to the spaced apart side sills, one of said rearwardly convergent flanges being so arranged as to constitute a floor plate support and attaching element.

65 8. A one-piece end member for rail cars provided with spaced apart side sills and comprising, a substantially vertical web extending from side sill to side sill, spaced apart outwardly directed flanges extending from one side of said 70 web and adapted to support a bumper element, rearwardly convergent flanges extending from the opposite side of said web, side walls connecting the ends of said convergent flanges and web and being adapted for attachment to the spaced apart side sills, and bracing means intermediate 75

said side walls for connecting said web and convergent flanges.

9. A one-piece end member for rail cars comprising, a substantially vertical web, spaced apart outwardly directed flanges extending from one 5 side of said web and adapted to support a bumper element, rearwardly convergent flanges extending from the opposite side of said web, side walls connecting the ends of said convergent flanges and web and being adapted for attachment to 10 the car structure, bracing means intermediate said side walls for connecting said web and convergent flanges, and centering means in alignment with said bracing means adapted to receive a bumper spring. 15

10. A one-piece end member for rail cars comprising, a substantially vertical web, spaced apart outwardly directed flanges extending from one side of said web and adapted to support a bumper element, rearwardly convergent flanges extending from the opposite side of said web, side walls connecting the ends of said convergent flanges and web and being adapted for attachment to 20 the car structure, bracing means intermediate said side walls for connecting said web and convergent flanges, spring centering means on said web in alignment with the bracing means and means connecting said outwardly directed flanges and web on either side of said centering means 25 to form a spring pocket. 30

11. A one-piece end member for rail cars comprising, a substantially vertical web, spaced apart outwardly directed flanges extending from one side of said web and adapted to support a bumper element, spaced apart rearwardly directed 35 flanges extending from the opposite side of said web, side walls connecting the ends of said flanges and web and being adapted for attachment to the car structure, bracing means intermediate said side walls for connecting said web and rearwardly directed flanges, and centering means in alignment with said bracing means adapted to receive a bumper spring. 40

12. A one-piece end member for rail cars comprising, a substantially vertical web, spaced apart 45 outwardly directed flanges extending from one side of said web and adapted to support a bumper element, spaced apart rearwardly directed flanges extending from the opposite side of said web, side walls connecting the ends of said 50 flanges and web and being adapted for attachment to the car structure, bracing means intermediate said side walls for connecting said web and rearwardly directed flanges, spring centering means on said web in alignment with said 55 bracing means, and means connecting said outwardly directed flanges and web on either side of said centering means to thereby form a spring pocket. 60

13. A one-piece end member for rail cars comprising, a substantially vertical web, spaced apart flanges extending outward from one side of said web and adapted to receive a combined spring draft and bumper unit, spaced apart rearwardly directed flanges extending from the opposite side 65 of said web and substantially coextensive with said web, one of said last named flanges being connected to the web between the upper and lower edges thereof. 70

14. A one-piece end member for rail cars comprising, a substantially vertical web, spaced apart flanges extending outward from one side of said web and adapted to receive a combined spring draft and bumper unit, spaced apart upper and lower rearwardly directed flanges extending from 75

the opposite side of said web, one of said last named flanges being connected to the web intermediate its upper and lower edge portions, and bracing means connecting said last named flanges and web.

15. A one-piece end member for rail cars comprising, a substantially vertical web, spaced apart flanges extending outwardly from one side of said web and adapted to receive a combined 10 spring draft and bumper unit, spaced apart upper and lower rearwardly directed flanges extending from the opposite side of said web, one of said last named flanges being connected to the web intermediate its upper and lower edge

15 portions, bracing means connecting said rearwardly directed flanges and the lower portion of the web, and additional bracing means connecting said upper flange and the upper portions of the web.

20. 16. In a mine car, side sills, and an end construction comprising a one-piece member having a substantially vertical web, spaced flanges extending horizontally outward from said web and so formed as to support a bumper element, 25 spaced apart rearwardly directed flanges extending from the opposite side of said web, one of said last named flanges having at least a portion thereof inclined downwardly with respect to the other flange for attachment to the car 30 floor, said member extending between the side sills and having relatively wide side flanges extending upwardly and downwardly from the inclined portion adapted for attachment to said side sills.

35. 17. In an end dump mine car, side sills, and an end structure extending between said side sills and comprising a unitary member having a substantially vertically arranged web, spaced flanges projecting beyond the ends of the side 40 sills from one side of said web and so formed as to support a bumper element, spaced flanges extending rearwardly from the opposite side of said web, one of said last named flanges having at least a portion thereof inclined downwardly 45 whereby to provide a deflecting means for guiding lading out of the car on end dumping, and side walls extending upwardly and downwardly from the inclined portion and connecting the end portions of said last named flanges and arranged 50 for attachment to the side sills.

55. 18. A one-piece end member for rail cars comprising an upright web extending substantially continuously between the car side sills and connected therewith, spaced apart flanges extending horizontally outward from one side of said web and adapted to support a bumper element, spaced apart rearwardly directed flanges extending from the opposite side of said web, one of said last named flanges having at least a portion thereof inclined downwardly toward the other flange and arranged for attachment to the car floor and constituting a part of the latter, spaced apart bracing members connecting said web and rearwardly directed flanges, and additional spaced apart bracing members connecting said outwardly directed flanges, thereby forming pockets for the reception of bumper springs.

60. 19. In a rail car construction, an end member comprising, a unitary casting formed to provide a substantially vertical web, spaced flanges projecting from one side of the web, upper and lower convergent flanges projecting from the opposite side of said web, and centering means on said web between said spaced flanges adapted to re-

ceive a bumper spring, one of said convergent flanges being secured to the car floor.

20. In a rail car construction, an end member comprising, a unitary casting formed to provide an upright web extending substantially continuously between the car side sills and connected therewith spaced flanges projecting from one side of the web, convergent flanges extending from side to side of the casting and projecting from the opposite side of said web, spaced apart 10 bracing means connecting said flanges, the bracing means connecting said outwardly projecting flanges forming pockets for the reception of bumper springs.

21. An end member for end dump mine cars 15 comprising a unitary construction embodying a web formed to extend between mine car side sills, attaching flanges formed with the web and arranged for extended contact with said side sills, a flange inclined downwardly and rearwardly 20 from the web and extending between and connected to the attaching flanges and constituting a lading supporting deflector, and supporting elements projecting from the said member and so arranged as to seat upon the side sills to support 25 said member.

22. An end member for rail cars comprising a unitary construction embodying a web extending continuously between the car side sills and being provided with oppositely directed flanges, certain of said flanges being formed to support a bumper element and the remaining flanges being at least in part convergent and at least one thereof arranged for attachment to a car floor, and side walls connecting said flanges and web 35 and so arranged as to be secured to car side sills.

30. 23. An end member for rail cars comprising a unitary construction embodying a web having oppositely directed flanges, certain of said flanges being formed to support a bumper element and the remaining flanges being at least in part convergent and at least one thereof arranged for attachment to a car floor, side walls connecting said flanges and web and so arranged as to be secured to car side sills, and means projecting 40 from opposite side portions of said end member so formed and arranged as to rest upon the upper portions of the side sills whereby said member is supported.

45. 24. An end member for rail cars having spaced 50 apart side sills and comprising, a unitary construction embodying a web extending continuously between the car sills and having bumper supporting means projecting from one surface thereof and flanges projecting from the opposite surface 55 thereof, said flanges being at least in part convergent with one thereof arranged for attachment to the car floor, and side walls connecting said flanges and web and so arranged as to be secured to the car side sills.

60. 25. An end member for rail cars having spaced apart side sills and comprising, a unitary construction embodying a web extending continuously between the car sills and having bumper supporting means projecting from one surface 65 thereof, and upper and lower convergent flanges substantially coextensive with the web and projecting from the opposite surface thereof, and means at the end portions of said flanges for connecting said member to the car side sills, one of 70 said flanges being formed for attachment to the car floor.

WILLIAM F. DIETRICHSON.
